ATT'YS.

UNITED STATES PATENT OFFICE.

LUTHER C. RISHEL, OF LOS ANGELES, CALIFORNIA.

AUTOMATIC WATER VALVE.

Application filed January 4, 1923. Serial No. 610,727.

My invention relates to automatic gas control devices employed in water heating systems for controlling the flow of gas to the burner in accordance with the flow of water through the system.

In automatic gas control devices of the character heretofore proposed, they have failed to operate successfully for any protracted period because of water leaking from the water valve through the gas valve and into the gas line, thus extinguishing the burner. This has been due, in the main, to faulty packing of the water valve, and the arrangement of the water valve with respect to the gas valve. Further, in such gas control devices, the connecting mechanism between the water valve and the gas valve has been such as to require a relatively high water pressure in order to actuate the valves so that they are incapable of success in systems having a relatively low water pressure.

It is a purpose of my invention to provide an automatic gas control which positively prevents water entering the gas line, and which is sufficiently sensitive to insure of its proper operation at all times irrespective of the degree of water pressure.

Although I have herein shown and described only one form of gas control device embodying my invention, it is to be understood that various changes and modifications may be made herein without departing from the spirit of the invention and the spirit and scope of the appended claims.

In the accompanying drawings,

Figure 1 is a view showing in vertical section one form of gas control device embodying my invention,

Figure 2 is a plan view partly in section of the gas control device shown in Figure 1,

Figure 3 is a detail sectional view taken on the line 3—3 of Figure 1,

Figure 4 is a vertical sectional view taken on the line 4—4 of Figure 1.

Referring specifically to the drawings in which similar reference characters refer to similar parts, my invention in its present embodiment comprises a casting which is constructed to permit of its being cast at a single operation, and this casting in the present instance comprises a water valve casing 15 and a gas valve casing 16, connected to the latter by means of an arm 17. The casing 15 is provided with a water inlet 18, as shown in Figure 2, and a water out-

let 19, as shown in Figure 1, a threaded nipple 20 threadedly engaging the casing 15 for the purpose of permitting the attaching of a pipe which conveys water to the usual heating coil of a heating system of this character. As clearly shown in Figure 1, one end of the casing 15 is provided internally with a projection 21 constituting a seat for a water valve 22. The casing 15 is also formed externally with a projection 23, and these projections 21 and 23, as well as the casing 15, are bored to receive a stem 24 of the valve 22. The projection 23 is threaded externally to receive a cap 25 for confining a packing 25^a within the projection and to thereby effectively seal the stem 24 against leakage of water from the casing 15.

The valve 22 is beveled at one end as indicated at 26, and this same end is recessed to accommodate a resilient washer 27 formed of rubber or other suitable material and arranged to engage the seat 21 when the valve is in closed position. This washer 27 cooperates with the packing 25^a in preventing the passage of water through the bore for the stem 24. The beveled end 26 is designed to cooperate with the beveled annular portion 28 of the valve casing 15 so that when the valve is in open position as shown in Figure 2, the water admitted to the casing from the inlet 18 will be evenly discharged into the casing and outlet 19.

The gas valve casing 16 includes a gas inlet 29 and a gas outlet 30, the gas inlet communicating with the inlet chamber 31 and the gas outlet communicating with an outlet chamber 32. These two chambers 31 and 32 are formed by means of a partition 33 provided with a port 34 controlled by a gas valve 35. The valve 35 is secured to a head 36 by means of a screw 37, and the head 36 is in turn fixed to a stem 38 slidably mounted in a bearing 39. The head 36 has its sides concaved as indicated at 36^a in Figure 3 for the purpose of allowing the free passage of gas through the port 34 when the valve 35 is in open position. The valve 35 is normally urged to closed position with respect to the port 34 by means of a spring 40 embracing the head of the screw 37 at its upper end and a projection 41 at its lower end. The projection 41 is formed on the inner side of a screw plug 42 fitted within the casing 16. The valve 35 is provided with an annular flange 35^a which is adapted to cooperate with a similar flange 34^a formed in

the wall of the port 34 in effecting the closing of the port to prevent the passage of gas from the chamber 31 to the chamber 32.

The stem 38 is provided at intervals with 5 annular grooves 38^a which are designed to receive vaseline or a similar sealing agent for preventing the leakage of gas through the bearing 39. The valve stems 24 and 38 are of sufficient length to project from the 10 casings 15 and 16, respectively, and for effecting the automatic operation of the gas valve upon actuation of the water valve, the following mechanism is provided.

As clearly shown in Figure 1, a bell crank 15 lever 43 is pivoted upon an ear 44 formed on the casing 16, and the upper arm of the lever 43 is bifurcated to receive the outer end of the valve stem 24. A coiled expandable spring 45 is interposed between the cap 25 and the lever 43, and a nut 46 is threadedly mounted upon the stem 24 for effecting an adjustment of the lever 43 with respect to the stem 24 as will be understood. A washer 47 is interposed between one end of 25 the spring 45 and the lever 43, as clearly shown in Figure 1. The other arm of the lever 43 engages the upper end of the stem 38, whereby it will be seen that movement of the lever 43 through movement of the stem 30 24 will effect movement of the stem 38.

In operation, the water valve 22 and the gas valve 35 are normally urged to closed position under the action of the springs 45 and 40. When the pressure of the water within the casing 15 is reduced by dispensing water from the casing, the valve 22 will respond to the pressure at the other side of the valve, thus moving to open position against the action of the spring 45. With 35 the valve 22 in open position as shown in Figure 2, the lever 43 is rocked to depress the lower arm and thereby the stem 38 against the tension of the spring 40 to open the valve 35. With the valve 35 opened, it 40 will be clear that the gas within the chamber 31 will be admitted to the outlet chamber 32 and ultimately to the burner of the system. It will be understood that the gas valve 35 will be opened a distance corresponding to the opening in the water valve 50

22 so that the supply of gas to the burner will be in accordance with the water discharged from the casing 15.

For the purpose of equalizing the pressure of water on the opposite sides of the valve 22, a duct 22^a is formed in the valve 22 as clearly shown in Figure 1, and it will be understood that through the medium of this duct, the water at opposite sides of the valve will be of equal pressure when the valve is 60 in closed position.

The possibility of the water entering the gas line through the bearing 39 is extremely remote. However, to positively prevent such an occurrence, that portion of the casing 16 adjacent the stem 38 is provided with a raised portion 16^a so that should any water accumulate on top of the casing 16, it cannot seep between the stem 38 and the bearing 39. 65

I claim as my invention:

1. A gas control device comprising a water valve casing, a water valve within said casing, having a duct there-through for equalizing the water pressure, a gas valve 75 casing disposed at an angle with respect to the water valve casing, a gas valve within the gas valve casing, stems extending from the casings and connected to the valves, a lever pivoted on one of the casings and engaging one of the stems, a spring interposed between one casing and said lever and surrounding the other stem, and a nut threaded on said stem and engaging the lever for the purpose described. 80

2. A gas control device comprising a water valve casing, a water valve within said casing, a gas valve casing, a gas valve within the gas valve casing, stems extending from the casings and connected to the valves, a lever pivoted on one of the casings and engaging one of the stems, a spring interposed between one casing and said lever and surrounding the other stem, and a nut threaded onto said stem engaging the lever for the purpose described. 85

In testimony whereof I have signed my name to this specification.

LUTHER C. RISHEL.
